UNITED STATES PATENT OFFICE.

REUBEN HALEY, OF BEAVER, PENNSYLVANIA, ASSIGNOR TO THE UNITED STATES
GLASS COMPANY, OF PITTSBURGH, PENNSYLVANIA, A CORPORATION OF PENN-
SYLVANIA.

DESIGN FOR A GLASS ARTICLE.

50,349.

Specification for Design.

Patented Feb. 20, 1917.

Application filed December 2, 1916. Serial No. 134,777. Term of patent 7 years.

To all whom it may concern:

Be it known that I, REUBEN HALEY, a citizen of the United States, and residing at Beaver, in the county of Beaver and State of Pennsylvania, have invented a certain new, original, and ornamental Design for a Glass Article, of which the following is a specification, reference being had to the accompanying drawings, forming a part thereof, whereby—

Figure 1 is a view in top plan of a glass article embellished with the new design, and Fig. 2 is a side elevation of the same.

No claim is made herein for the shape or outline of the article. The design, which consists of the configuration shown, may be formed in or on the surface of various glass articles.

I claim:

The ornamental design for a glass article, substantially as shown and described.

REUBEN HALEY.
